UNITED STATES PATENT OFFICE

WILLIAM A. JONES, OF WEST NEW BRIGHTON, NEW YORK, ASSIGNOR TO THE BABCOCK & WILCOX COMPANY, OF BAYONNE, NEW JERSEY, A CORPORATION OF NEW JERSEY

SUPERHEATER BOILER

Application filed July 29, 1922. Serial No. 578,294.

My present invention relates to steam boilers in which a superheater is provided.

One of the objects of my invention is to provide means by which the superheater may be suspended from boiler parts. Another object of my invention is to provide means by which a superheater may be suspended amongst water tubes from such water tubes or associated boiler parts with baffles to protect the headers of the superheater.

With these and other objects in view, my invention consists in the combinations and arrangements hereinafter described and more specifically pointed out in the appended claims.

In the drawings, Figure 1 is a sectional side elevation of one form of water tube boiler having my invention embodied therein; Figs. 2 and 3 are enlargements of parts shown in Fig. 1 with modifications; Fig. 4 is an elevation, partly in section, of a portion of the water tube boiler similar to that shown in Fig. 1, but with the superheater of a slightly different construction; Fig. 5 is a section of Fig. 4 taken on the line 5—5 of Fig. 4; Fig. 6 is a view similar to Fig. 4 showing a modified form of my invention; Fig. 7 is also similar to Fig. 4 showing still another modification; Fig. 8 is a view similar to Fig. 4 in which the superheater headers are suspended directly from the water tubes; Fig. 9 is a section on line 9—9 of Fig. 8; Fig. 10 is a portion of Fig. 8 taken on line 10—10 of Fig. 12; Fig. 11 is a plan view of Fig. 10 with the header omitted; Fig. 12 is a section on line 12—12 of Fig. 11; Fig. 13 is an enlargement of a portion of Fig. 9; Fig. 14 is a section on line 14—14 of Fig. 13; Fig. 15 is an end view of one of the plates shown in Fig. 13, and Fig. 16 is an enlarged sectional view of one of the fastening devices used in Fig. 13.

Like reference characters indicate like parts in the several views.

In the boiler shown in Fig. 1, which I have chosen for purposes of illustration, the water tubes are horizontally inclined and formed into a lower bank 10 and an upper bank 11 with a space 12 between them. The tubes are connected by the usual headers to a steam and water drum 13. The boiler has a furnace

having a high furnace chamber 14 over a pair of opposed underfeed stokers 15 and 16.

Located in the space 12 is a double superheater having an inlet header 17 extending across this space between the side walls of the boiler setting and connected by a pipe 18 with the steam space of the drum 13. Similarly, an outlet header 19 extends across this space and also auxiliary headers 20 and 21, these latter being connected with each other and also through U-tubes 22, 22, with the outlet and inlet headers. The U-tubes extend in the same general direction as the water tubes, and the boiler is provided with a baffle 23 along the uppermost row of tubes of the lower bank 10 to a point adjacent the superheater headers. Baffles 24 and 25 direct the gases back and forth across the tubes after they have passed the superheater and direct the gases to the gas outlet 26. The spaces between the several headers may be closed by suitable baffles, so that such baffles and the headers constitute an extension of the baffle 24 to the baffle 23.

In modern practice, the space between the side walls of boiler settings is quite wide and, because of the varying conditions which may arise within the superheater, the headers are subject to strains which tend to distort them. I provide means by which these headers may be supported throughout their length, and yet in such a manner that a relative motion, due to expansion and contraction of the headers, will be permitted in each header in relation to the other header and also to the boiler parts.

In Fig. 2, I have shown one form of my invention, in which the header 19 has formed thereon a fin 27 which may be divided into sections, as shown, for instance, in Fig. 5. This fin or these fins may be joined to the header body 19 by welding either electrically or autogenously. The baffle 24 will be provided, as usual, with a backing plate 28, and the fin 27 will be placed against this plate and connected thereto by bolts 29 passing through holes in the fin 27 and holes in the plate 28. Preferably, one or both sets of these holes will be slotted in a direction parallel to the direction of the header, so that the header may move lengthwise of its axis without

straining or tearing apart the suspension fasteners. As shown in Fig. 2, the fin 27 is protected from the heat of the first pass by a heat insulator, such as the plastic asbestos composition 30.

Fig. 3 is similar to Fig. 2 except that the header is supported by a suspension fastener in the form of metal strips 31 passing around the header and connected to the plate 28 by bolts 29 in the manner just described. It will be understood that as many of these strips 31 as may be necessary are placed along the length of the header. Instead of the plastic composition 30, a tile or block 32 may be used to protect the strips.

In Fig. 1, the header 17 is supported on the water tubes in the manner shown best in Fig. 6, and which will be described in connection with that figure.

20 In the arrangement shown in Fig. 4, the superheater is single with the outlet header 19 connected to the inlet header 17 by a double row of tubes 22. The inlet header 17 is supported from the plate 28 in the manner already described in connection with Fig. 2, and is also provided with a fin or fins 33 on the side opposite the fins 27 and formed in a similar manner. The outlet header 19 is provided with fins 34 on its upper side similar to the upper fins of the inlet header 17, and the fins 33 and 34 are connected by fasteners 35 passing through holes in the two fins. One of these sets of holes may be slotted longitudinally of the axes of the headers. A baffle 36 is placed partly surrounding and in front of the headers to connect the lower end of the baffle 24 with the longitudinal baffle 23. In the form just described, both headers are suspended from the plates 28 which, in turn, it will be understood, are engaged by the water tubes in the usual manner and as best shown in Fig. 5.

In the arrangement shown in Fig. 6, the inlet header 17 is beneath the baffle 24 and connected to the plates 28 in the manner which I have just described, by means of the fins 27. A second fin 37 extends from the lower side of this header into the horizontal baffle 231 forming a more complete connection with that baffle and also to better support the baffle 38 in front of the header. Plates 50 may be bolted to the fin 37 to suspend the superheater tubes 22, these plates having holes through which such tubes pass in a manner which will be described more in detail in connection with Figs. 9 to 16. Members 51 may be provided beneath the header 19 to transmit some of the weight thereof to the tubes 10, these members having a construction which will be pointed out more specifically hereinafter.

In Fig. 6, the outlet header 19 is supported directly from the water tubes by means of suspension hangers 39 connected to a fin 40

and extending through pieces 41 resting on top of one or more of the water tubes.

In the arrangement shown in Fig. 7, I use cylindrical members or studs, screwed or otherwise connected to the headers and welded thereon to form a steam-tight joint. The inlet header 17 has an L-shaped member 42 formed as a bolt on its upper end which passes through a hole in the plate 28. This hole may be slotted longitudinally to permit longitudinal motion of the header 17. Similarly, the header 19 is provided with a stud-like member 43 which passes through a plate 44 resting on one or more of the water tubes. It will be understood that as many of the pieces 42 and 43 may be provided spaced along the respective headers as may be necessary to support such headers and prevent their sagging.

In the arrangement shown in Fig. 8, the headers 17 and 19 are located further away from the lower end of the baffle 24 and, instead of the header 17 being connected directly to a portion of the baffle 24 through the plates 28, it is suspended from the tubes 11 by means of suspension members 52, the weight of the header, of course, being transmitted through these tubes to the entire group of tubes 11 through the plates 28. The header 19 is suspended by the members 39 and the pieces 41' from the upper tubes 11 and also rests on one or more members 51 which, in turn, rest on the tubes 10 and preferably have the shape shown in cross-section in Fig. 12. It will be noted that the members 51 are unattached to the tubes 10 and are provided with recesses in their upstanding flanges 53 for the header 19. In the form shown in Fig. 8, the right-hand end of the members 51 rests against the downtake headers of the boiler, so that the horizontal component of the weight of the header 19 will be transmitted to this vertical header. It should be noted, however, that as shown in some forms of my invention, as for instance, in that of Fig. 7, it will be unnecessary to extend the member 51 entirely to the boiler proper, because the same effect may be obtained by inserting a portion of the baffle between the end of the member 51 and the boiler header.

110 Preferably, the hangers 39, as well as hangers 43, are positioned to pull at right-angles to the tubes 11, to avoid any tendency to draw the pieces 41 or 41' along the tubes, as might be the case if the hangers were vertical. Any 115 tendency of the headers to move to the right in Figs. 6, 7 and 8 will be resisted by the members 51. If desired, however, the hangers 41 and 41' may be vertical.

In the arrangement shown in Fig. 8, the baffle 23 extends from the boiler header to the superheater header 19, a baffle 231 extends from the header 19 to the header 17 and a baffle 232 extends from the header 17 to the baffle 24. The combination of these separate 125 130

baffles, together with the headers, constitute therefore a continuous baffle extending from the downtake headers of the boiler to the cross baffle 24.

5 In the arrangement shown in Fig. 8, the fin 37 of the header 17 has connected to it a series of plates 50, each provided with half-round recesses in each side in order to fit between the tubes 22 of the superheater, and 10 preferably having their edges formed as shown best in Fig. 14, so as to provide an overlap. The upper ends of the plates are provided with openings through which pass fasteners as 55, which may have key-shaped 15 heads 56 by which the fasteners may be readily released. As will be obvious from an inspection of Figs. 9 and 13, when the plates 50 are attached to the fin 37, they will support the lower portion of the U-tubes 22, and at the 20 same time, will stiffen the entire combination, providing a substantially continuous plate made up of the plates 50 on the lower side of the header 17.

In the arrangement shown in Fig. 8, the 25 tubes 22 may also be supported by the plates 501 which will be similar to plates 50, but will have their upper ends bent as shown in Fig. 8, to be attached to the lower portion of the plates 28.

30 In each of the arrangements which I have described, it will be seen that I have provided a means by which superheater headers extending across the boiler beneath some of the tubes thereof may be suspended from the 35 boiler parts, such as baffles or tubes, and so that the possibility of sagging of the headers between their end supports will be removed. At the same time, the headers are free to move longitudinally as they will do under 40 the varying conditions to which a superheater is subjected. It will also be seen that the superheater boxes form a part of baffles which extend across the superheater space, these baffles at the same time protecting one of the 45 faces of the superheater boxes so that the possibility of distortion arising from the higher temperature in one pass than in another will be eliminated. In each of the arrangements shown, it will also be noted that 50 when the baffle is made, as indicated, of plates 28, as shown best in Fig. 5, in which these plates extend upwardly and are, in turn, engaged by a plurality of water tubes 11, the weight of the superheater when connected 55 to the water tubes, will, in fact, be carried not by the lower water tubes only, but by all of the water tubes. The baffle plates 28, by connecting the several water tubes, form what is, in effect, a beam made up of all of 60 the water tubes, and therefore strong enough to resist distortion under the weight of the superheater. This effect is obtained regardless of whether the superheater headers are connected directly to the plates 28, as shown 65 in all of the figures except Fig. 8, or whether

the headers are connected to a short length of tubes between the vertical baffle and the downtake headers, as shown in Fig. 8. In either case, it is obvious that the lower row of tubes 11 will not sag under the weight of 70 the superheater as would be the case if the middle portion of these tubes were not connected to all of the tubes above them through the plates 28.

It will be understood that the forms of 75 my invention which I have shown are merely illustrative, and that the constructions may be widely varied. By forming the suspension member as substantially an integral part of the boxes, I produce a construction which 80 is not only simple, but which is capable of withstanding the action of the heat of the boiler.

I claim:

1. In a superheater water tube boiler, a 85 superheater having a header extending beneath some of the water tubes and means to suspend said header from the tubes of said boiler, the parts being constructed and arranged to permit relative movement between 90 said header and said water tubes.

2. In a superheater water tube boiler, a 95 superheater having a header extending beneath some of the water tubes and means to suspend said header at a point intermediate its ends from the tubes of said boiler above it, the parts being constructed and arranged to permit relative movement between said header and said water tubes.

3. In a superheater water tube boiler, a 100 superheater having a header extending across and beneath some of the water tubes and means to suspend said header from the tubes of said boiler, the parts being constructed and arranged to permit relative movement 105 between said header and said water tubes.

4. In a superheater water tube boiler, a 110 superheater having a header extending across and beneath some of the water tubes and means to suspend said header at a point intermediate its ends from the tubes of said boiler above it, the parts being constructed and arranged to permit relative movement between said header and said water tubes.

5. In a superheater water tube boiler, a 115 superheater having a header extending beneath some of the water tubes and means to suspend said header from the tubes of said boiler above it, said means comprising a plurality of members spaced along the header, 120 the parts being constructed and arranged to permit relative movement between said header and said water tubes.

6. In a superheater water tube boiler, a 125 superheater having a header extending beneath some of the water tubes and means to suspend said header from the tubes of said boiler above it, said means comprising a plurality of members spaced along the header 130 and connected to the header so as to permit

- it to move longitudinally relatively to the boiler parts.
7. In a superheater water tube boiler, a superheater having a header extending beneath some of the water tubes and means to suspend said header from the tubes of said boiler above it, said means comprising a suspension member permanently connected to the header.
- 10 8. In a superheater water tube boiler, a superheater having a header extending beneath some of the water tubes and means to suspend said header from the tubes of said boiler above it, said means comprising a suspension member permanently connected to the header, and connecting devices between said suspension member and the boiler parts adapted to permit the header to move longitudinally relatively to the boiler parts.
- 15 9. In a superheater water tube boiler, a superheater having a header extending beneath some of the water tubes and means to suspend said header from the tubes of said boiler above it, said means comprising a plurality of suspension members spaced along the header and permanently connected thereto.
- 20 10. In a superheater water tube boiler, a superheater having a header extending beneath some of the water tubes, means to suspend said header from the boiler parts above it, said means comprising a plurality of suspension members spaced along the header and permanently connected thereto, and connecting devices between the suspension members and the boiler parts adapted to permit the header to move longitudinally relatively to the boiler parts.
- 25 11. In a horizontally inclined water tube boiler having a baffle plate extending across the tubes, a superheater having a header extending across and beneath some of the water tubes and adjacent the lower end of said baffle plate, and means to suspend said header from said baffle plate.
- 30 12. In a horizontally inclined water tube boiler having a baffle plate extending across the tubes, a superheater having a header extending across and beneath some of the water tubes and adjacent the lower end of said baffle plate, and means to suspend said header from said baffle plate at a point intermediate its ends.
- 35 13. In a horizontally inclined water tube boiler having a baffle plate extending across the tubes, a superheater having a header extending across and beneath some of the water tubes and adjacent the lower end of said baffle plate, and means to suspend said header from said baffle plate at a point intermediate its ends.
- 40 14. In a horizontally inclined water tube boiler having a baffle plate extending across the tubes, a superheater having a header extending across and beneath some of the water tubes and adjacent the lower end of said baffle plate, and means to suspend said header from said baffle plate.
- 45 15. In a water tube boiler, two groups of water tubes spaced apart, a cross baffle and baffle plate in the group of tubes above the space, a superheater in the space having headers extending across the tubes and beneath some of the tubes, and means to suspend the headers from the boiler parts, one of the headers being adjacent the lower end of said cross baffle plate and suspended therefrom.
- 50 16. In a water tube boiler, two groups of water tubes spaced apart, a cross baffle and baffle plate in the group of tubes above the space, a superheater in the space having headers extending across the tubes and beneath some of the tubes, means to suspend the headers from the boiler parts, one of the headers being adjacent the lower end of said cross baffle plate and suspended therefrom, and an auxiliary baffle connecting with the lower end of said cross baffle and extending across said space at one side of the headers.
- 55 17. In a water tube boiler, two groups of water tubes spaced apart, a cross baffle and baffle plate in the group of tubes above the space, a superheater in the space having headers extending across the tubes and beneath some of the tubes, and means to suspend the headers from the boiler parts, one of the headers being adjacent the lower end of said cross baffle plate and suspended therefrom, said suspending means comprising a plurality of suspension members spaced along the headers and permanently attached thereto.
- 60 18. In a water tube boiler, a plurality of groups of water tubes spaced apart, a baffle comprising a baffle plate extending across one group of said tubes and the space between the groups, a superheater having a header located in said space, said header being suspended from said baffle plate and constituting a portion of said baffle.
- 65 19. A superheater header comprising a tubular member and projecting fins extending along the header and on opposite sides thereof and permanently attached thereto, one of said fins being a supporting means for said header.
- 70 20. In a superheater water tube boiler having horizontally inclined water tubes, a superheater header extending across some of said water tubes and a saddle member resting on the water tubes and supporting the header, the parts being constructed and arranged to

permit relative movement between said header and said water tubes.

21. In a superheater water tube boiler having horizontally inclined water tubes connected to headers, a superheater header extending across some of said water tubes and a saddle member resting on and unattached to the water tubes and supporting the header, and means whereby the downtake header is caused to resist movement of the saddle toward said header.

22. In a superheater water tube boiler, a superheater having inlet and outlet headers extending across the boiler, U-tubes connecting said headers and means suspended from one of the headers to support the U-tubes at points near their entrance into the other header.

23. In a superheater water tube boiler, a superheater having inlet and outlet headers extending across the boiler, U-tubes connecting said headers and means suspended from one of the headers to support the U-tubes at points near their entrance into the other header, said means comprising plates encircling said superheater tubes and connected to said header.

24. In a horizontally inclined water tube boiler, a baffle having a metallic plate engaging a plurality of water tubes in a vertical direction, a superheater having a header extending across and beneath some of the water tubes and adjacent the lower end of said plate, and means to suspend the header from said plate.

25. In a horizontally inclined water tube boiler, a baffle having a metallic plate engaging a plurality of water tubes in a vertical direction, a superheater having a pair of headers extending across and beneath some of the water tubes and adjacent the lower end of said plate, U-tubes connecting said headers, means to suspend one of the headers from said plate, and means to suspend the U-tubes from said header at a point adjacent the other header.

26. In a water tube boiler comprising rows of water tubes, a superheater, and a support for said superheater comprising members engaging water tubes in a plurality of horizontally extending rows.

27. In a water tube boiler comprising rows of water tubes, a superheater comprising rows of tubes, and a support for said superheater comprising members engaging water tubes in a plurality of rows and also engaging superheater tubes in a plurality of rows.

28. A steam boiler having banks of water tubes connected to water chambers with a space between the banks, and a superheater including headers and superheater tubes and having at least the major portion of its heating surface within said space, the weight of said headers and said superheater tubes being separately sustained by some of said water

tubes, the parts being constructed and arranged to permit relative movement between the headers of said superheater and said water tubes.

29. A steam boiler having banks of water tubes connected to water chambers with a space between the banks, and a superheater including headers and superheater tubes and having at least the major portion of its heating surface within said space, said headers and said portion being separately sustained by some of said tubes, the parts being constructed and arranged to permit relative movement between the headers of said superheater and said water tubes.

30. A steam boiler having banks of water tubes connected to water chambers with a space between the banks, a tubular superheater having at least the major portion of its tubular heating surface within said space and having inlet and outlet headers with tubes connecting said headers, the weight of said inlet and outlet headers and said tubular heating surface being separately sustained by some of said tubes, the parts being constructed and arranged to permit relative movement between the headers of said superheater and said water tubes.

31. A steam boiler having banks of water tubes connected to water chambers with a space between the banks, a tubular superheater having at least the major portion of its tubular heating surface within said space and having inlet and outlet headers with tubes connecting said headers, one of said headers being at a higher level than the other, a support for the lower header resting on the lower bank of boiler tubes, and a support for the upper header connected to tubes of the upper bank.

32. A steam boiler having banks of horizontally inclined water tubes spaced apart, water chambers connected to the ends of said water tubes, a superheater in said space with an upper and a lower header extending through said space and across the water tubes, superheater tubes extending longitudinally of said water tubes and connecting said headers, said lower header being adjacent the water chamber connected to the lower ends of the water tubes, a support for said lower header resting on the lower bank of water tubes and arranged to transmit its horizontal thrust to the adjacent water chamber, and a suspension support for said upper header connected to the tubes of the upper bank of water tubes.

33. A steam boiler having banks of horizontally inclined water tubes spaced apart, water chambers connected to the ends of said water tubes, a superheater in said space with an upper and a lower header extending through said space and across the water tubes, superheater tubes extending longitudinally of said water tubes and connecting said headers

said lower header being adjacent the water chamber connected to the lower ends of the water tubes, a support for said lower header resting on the lower bank of water tubes and arranged to transmit its horizontal thrust to the adjacent water chamber, a refractory wall in front of said support and said lower header, a baffle between said lower and said upper headers, and a refractory wall in front of said upper header.

34. A water tube boiler having a setting enclosing the same, a superheater located within the setting and having a header extending beneath water tubes of the boiler, and connections for suspending said header from parts of the boiler heating surface extending above it, the parts being constructed and arranged to permit relative movement between said header and said parts of the boiler heating surface.
